WILLIAM M. SHAKESPEARE, OF SOUTH ORANGE, NEW JERSEY, ASSIGNOR TO ANA-
CONDA SALES COMPANY, OF NEW YORK, N. Y., A CORPORATION OF DELAWARE

METAL-PROTECTED ROOFING

Application filed July 17, 1929. Serial No. 378,963.

This invention relates to roof constructions and has to do more particularly with a roof built up of a plurality of layers of relatively inexpensive roofing material, together with a top layer of similar material, but provided with metal covering the normally exposed portions thereof, whereby the structure has the durability, resistance to fire, and desirable appearance of an all-metal roof. The metal-clad material of which the top layer above mentioned is formed and which is used in connection with other roofing products to produce the new roof is also capable of use alone for numerous purposes, such, for example, as siding and the like. This new roofing product comprises a base in the form of a web of fibrous material and a metal coating affixed thereto, the metal being of insufficient thickness to be used alone but sufficiently strong for the purpose for which it is used, inasmuch as it is backed and re-inforced by the base. This new material includes numerous other features of construction which will be made clear in the more detailed description to follow.

The new roof is made up of the usual foundation structure of roofing boards upon which are laid one or more layers of roofing material, such as roll roofing, in the form of asphalt-impregnated felt, the webs of roofing material being laid side by side with substantial overlap. Between the overlapping portions of the webs of each layer and also between adjacent layers is placed a suitable waterproof cementing compound, such as hot asphalt. Over the top of the uppermost of these layers of plain roofing material is placed a layer of metal-clad material, this layer being bound to the underlying layer by the cementing compound in the usual way.

The metal-clad material preferably takes the form of a web of asphalted felt with a strip of weather-resistant metal, such as copper, affixed to one surface thereof and covering substantially one-half the width of the felt along one edge, the metal projecting

slightly beyond that edge. In making the upper layer of the roof of this material, the webs are laid with a substantial overlap so that the exposed portion of each web is covered entirely by metal. These overlapping portions are bound together by the cementing compound and excess compound which is extruded flows out from between the layers and fills the space beneath the overhanging edge of the metal, providing a support for this edge and being to a large degree concealed thereby, and at the same time sealing the edge of the felt sheet and making a good joint.

In a roof made in the manner described, the entire exposed surface is covered by metal so that the harmful effect of the rays of the sun on the felt and asphalt is prevented. The metal-clad webs, firmly bound together by cementing material, have the appearance of sheets of metal, the extruded portions of the cementing compound being concealed so as not to impair the appearance of the roof.

For a better understanding of the new construction, reference may be had to the accompanying drawings, in which

Fig. 1 is a view in perspective of a roll of the new metal-clad roofing product;

Fig. 2 is a sectional view of this product transversely thereof;

Fig. 3 is a sectional view illustrating the manner in which two metal-clad webs are laid in overlapping relation;

Fig. 4 is a view in perspective and partly in section, illustrating the formation of the complete structure; and

Fig. 5 is a fragmentary view of parts illustrated in Fig. 3 but on a larger scale.

The new roofing material comprises a web 10 of felt, paper, or similar material commonly used for roofing purposes, impregnated or saturated with a water-proofing compound, such as asphalt, and a band 11 of a weather-resistant metal, such as copper, or the like, applied to one surface thereof. The band, as shown in Fig. 2, has a width approximately 85 90

one-half the width of the felt and it is affixed to the felt along one edge thereof with the metal projecting slightly beyond the edge of the felt, as illustrated at 12. The metal is very thin and it is affixed to the felt in any convenient manner, preferably by means of asphalt or other similar cementing compound. The felt employed for the purpose is relatively light in weight so that it is quite flexible and the metal is sufficiently thin so that its application to the felt does not impair the flexibility thereof to any substantial extent. As a result, the metal-clad material may be formed in webs of substantial length and shipped and handled in the form of rolls.

The new roof comprises the usual roofing boards 13 laid in any suitable or usual manner and on the surface of the boards is placed a layer of roofing material generally designated 14. This material is preferably made up of a plurality of felt webs of substantial weight and thickness. A convenient form of material for the purpose is roll roofing of standard width laid in overlapping stretches lengthwise of the roof, the first stretch 15 being laid with its edge even with the edge of the roofing boards and the next stretch 16 laid to overlap the stretch 15 for somewhat one-half its width. The extent of the overlap may vary with different conditions, but an overlap in excess of 50 per cent. is preferred for the best type of roof since this results in each stretch being overlain by two adjacent stretches and thus provides headlap. The successive lengths of roofing material are laid in place one after another until the entire surface of the roofing boards is covered. The overlapping portions of the adjacent webs of roofing are cemented together by hot asphalt or the like, and a layer 17 of the material is applied to the upper surface of the layer 14.

Over the first layer 14 of overlapping webs may be placed one or more layers 18 laid in a similar manner and over the uppermost of these layers is applied a coating of cementing material 19. The number of layers similar to 14 and 18 that are used will depend on the character of the roof, but ordinarily two or three such layers are satisfactory to give the roof a life which may be guaranteed for an extended term.

The roof is completed with metal-clad webs such as that illustrated in Fig. 1. These webs are laid side by side in overlapping relation in such manner that each web, such as that designated 20, overlaps that portion of the underlying web 21 which is not protected by metal and also a narrow portion of the metal coating on the web 21. The overlap preferred is illustrated in Fig. 3 where it will be seen that the web 20 overlies that portion 22 of the web 21 which is not protected by metal and also slightly overlaps the metal as illustrated at 23. The

first metal-clad web 24 is laid in position along the edge of the roof and the unmetalized portion thereof receives a coating of cementing material 25. The next layer 21 is then laid in place and bound to the underlying web by means of the cementing material. When the web 21 is placed in position and pressed firmly in place, the cementing material 25 between the webs is likely to be squeezed out to some extent, but this extruded cementing material collects beneath the overhanging portion of the metal band of the web 21, as illustrated at 26 (Fig. 5).

The metal which I prefer to employ for coating the webs takes the form of a band of copper of light weight, the copper having an attractive appearance and being highly resistant to the weather. Preferably each web is approximately 30" wide and the metal band is 15" wide. The metal band is applied along one edge so as to overhang the edge of the web to a slight extent, as, for example, $\frac{1}{8}$ " to $\frac{1}{4}$ ". If preferred, the material may readily be made in other dimensions, but the adoption of those mentioned provides a material which is convenient to handle and lay. While the metal employed is very light and flexible, the metal projects beyond the edge of the web to so slight an extent that when the material is rolled up the projecting portions of the metal in the numerous convolutions is not likely to become flattened against the edge of the web during handling. Even if such flattening should occur, the utility of the roofing construction is in no way impaired, since the metal, if folded against the edge of the felt, protects that edge against the action of the weather.

Ordinarily in laying the material, each metal-clad web will extend from one end of the roof to the other but where a pair of webs must be joined to complete a stretch, the two webs in the stretch, as, for example, those designated 27, 28, are placed in alignment with one web overlapping the other to a substantial extent, as, for example, 6".

It will be seen that in the new roof a high degree of protection is afforded by reason of the number of roofing layers that are employed, and at the same time the entire exposure of the completed roof is covered wholly by metal. Owing to the fact that the metal may be very thin, since it is supported by the felt base, the application of metal to the felt to be used in the upper layer of the roof does not add materially to the cost of the construction. Only a small amount of metal is required for a square of the roof, the metal being much thinner than would be necessary if it were used alone and without the felt to support it. In the new roof, the felt is wholly concealed and therefore no felt is directly exposed to the action of the sun. It has been ascertained that the actinic rays of the sun have a harmful effect on asphalt

and cause its eventual deterioration, but in the present roof the entire exposed surface of the felt is protected by metal and the metal not only adds greatly to the life of the roofing but also improves its appearance. Inasmuch as the sheet is affixed flat to the surface of the felt, the metal-clad material may be rolled smoothly into rolls suitable for commercial roofing and the material can be made cheaply and rapidly without elaborate apparatus. This material may be used for many purposes other than the one illustrated, as, for example, the material is suitable for use as siding, partitions in manufacturing structures, etc.

What I claim is:

1. A roofing material which comprises a web of fibrous material and a coating of weather-resistant metal on one surface only of the web, said coating covering a substantial part of said surface and projecting beyond the edge of the web along one side thereof.

2. A roofing material which comprises a web of fibrous material and a coating of weather-resistant metal on one surface only of the web, said coating covering a substantial part of said surface along one edge and leaving a substantial part of said surface exposed, the edge of said coating lying beyond said edge of the web.

3. A roofing material which comprises a web of impregnated roofing felt, and a band of weather-resistant metal on one surface only of the felt, the band having a width approximately one-half the width of the web and lying along one edge thereof with one edge of the metal extending beyond said edge of the web a relatively short distance.

4. In a built-up roof, the combination of one or more layers of roofing material and an upper layer of webs of metal-coated roofing material, each web carrying a longitudinal band of metal along one edge only of the web, this band being approximately half as wide as the web and projecting beyond said edge of the web, the webs lying in overlapping relation with their metal bands only exposed, and cementing material between the overlapping portions of said webs and beneath the projecting portion of each band of metal and in contact therewith.

5. In a built-up roof, an exposed layer comprising a plurality of webs of roofing material laid side by side in overlapping relation, each web carrying a longitudinal metal band on one surface thereof and of less width than the web, this band covering the exposed surface of said web and overlapped to a slight degree by the adjacent web, said band projecting to a slight distance beyond the edge of the web on which it is mounted, and cementing material at the end of said web and filling the space beneath the projecting portion of said band.

6. In a built-up roof, an exposed layer comprising laterally overlapping webs of roofing material, each web having a longitudinal band of metal along one edge only and covering substantially only the exposed portion of said web, said band projecting a short distance beyond said edge and cementing material between the overlapping portions of said webs and beneath the projecting portions of said bands to provide a seal at the edges of said webs.

In testimony whereof I affix my signature.
WILLIAM M. SHAKESPEARE.
